UNITED STATES PATENT OFFICE.

HARRY M. BROCK, OF NORTH YAKIMA, WASHINGTON.

DENTAL INSTRUMENT.

1,136,649.

Specification of Letters Patent. Patented Apr. 20, 1915.

Application filed February 19, 1914. Serial No. 819,667.

To all whom it may concern:

Be it known that I, HARRY M. BROCK, a citizen of the United States, and a resident of the city of North Yakima, State of Washington, have invented a certain new and useful Improvement in Dental Instruments, of which the following is a specification.

This invention relates to dental instruments and has for its principal object to provide means for more quickly attaching and detaching the bits or plugging points to the handle of a dental instrument.

The invention will be more fully described and explained in the following specification, illustrated in the accompanying drawings and pointed out in the appended claims.

In the drawings, Figure 1 is a fragmentary longitudinal sectional view of my device, with its plugging point removed. Fig. 2 is an end elevation of the same. Fig. 3 is a fragmentary view of the entering end of the plugging point.

Referring now more particularly to the drawings, reference numeral 22 designates the central shaft of a form of dental instrument for use in plugging teeth, which is recessed and threaded as shown, to receive a plunger bit 23.

The shank of my improved form of plunger bit is split, as indicated at 24 and 24^a, the portion 24^a being threaded as shown, and transversely through it is an aperture indicated at 25 in which is a pin 26 which is secured to a leaf spring 27 one end of which 30 may be upturned as at 28 and its opposite end secured by means of a screw 29 to the bottom of a slot which is indicated at 30. In order to change the plunger bits all that is necessary is to insert the split end 24 of the 35 same into the recessed portion of the shaft 1 and press said plunger bit firmly into place, the pin 26 snapping into the aperture 31 in the said portion 24, and to remove the plunger bit it is only necessary to lift up- 40 wardly upon the upturned end of the spring 27 until the free end of the pin 26 clears the aperture 31. The above described means is effective to secure a plunger bit in place with sufficient firmness for ordinary use, but 45 when it occurs that a more firm joint must be had the use of an ordinary plunger bit does not in anywise interfere therewith because in that case the portion 24^a may be removed and the ordinary plunger bit secured 50 in place as usual. As indicated, however,

the necessity for this does not frequently occur and the extra time required for removing the portion 24^a, whenever such necessity does occur, may therefore be said to be negligible.

The invention consists solely in the bit and applicant does not attempt to claim more than this.

I have described a particular form of embodiment of my invention but I am aware that many minor changes therein will readily suggest themselves to others skilled in the art without departing from the spirit and scope of the invention and I therefore desire to avoid being limited to the exact form shown and described.

What I claim is—

1. The combination with the internally threaded socket of a dental instrument, of a sectional bit and means for separating the sections of the bit while one of the sections remains screwed into the said socket, the said means including a fully threaded end upon one of the sections which is adapted to be screwed into the socket, the said section being split in the direction of its length and behind its fully threaded end, whereby a portion of the socket is left open when the said fully threaded end is in place, the other section of the bit being similarly split and adapted to be slipped into and out of the said open portion of the socket when the other section is in place.

2. The combination with the internally threaded socket of a dental instrument, of a sectional bit and means for separating the sections of the bit while one of the sections remains screwed into the said socket, the said means including a fully threaded end upon one of the sections which is adapted to be screwed into the socket, the said section being split in the direction of its length and behind its fully threaded end, whereby a portion of the socket is left open when the said fully threaded end is in place, the other section of the bit being similarly split and adapted to be slipped into and out of the said open portion of the socket, and means for holding the last mentioned section in place, said means including a spring-actuated pin.

HARRY M. BROCK.
